ADJUSTABLE ARTICLE OF FURNITURE

Filed Feb. 15, 1932

Fig. 1

UNITED STATES PATENT OFFICE

STEFAN SCHNEIDER, OF PHILADELPHIA, PENNSYLVANIA

ADJUSTABLE ARTICLE OF FURNITURE

Application filed February 15, 1932. Serial No. 592,981.

My invention relates to new and useful improvements in an adjustable article of furniture and more particularly to an article of furniture having an adjustable back and has for one of its objects to connect the lower end of a back frame or similar part to a body frame so that the upper end of said back frame can be moved into various positions and provide means to hold it in any one of the 10 adjusted positions.

Another object of the invention is to adjustably connect one frame to another and provide means, spring operated in one direction, to hold the adjustable frame in different 15 positions, the parts being so fashioned and assembled that the frames may be upholstered.

A further object of the invention is to provide the adjustable back frame of an article 20 of furniture with a pair of spring actuated bolts for holding said back frame in several adjusted positions, said bolts being operable manually against the action of the springs by a set of levers connected to a spring actuated rod slidably mounted in the back frame.

With these and other ends in view, this invention consists in the details of construction and combination of elements hereinafter set forth and then specifically designated by 25 the claims.

In order that those skilled in the art to which this invention appertains may understand how to make and use the same, I will describe its construction in detail, referring 30 by numerals to the accompanying drawing forming a part of this application, in which:

Fig. 1 is a perspective view of a chair frame with the upholstery removed illustrating an application of my invention.

Fig. 2 is an inner face view of one of the rear uprights of the body frame to show a keeper for one of the bolts.

Fig. 3 is an enlarged end view of one of the 45 bolts and its case.

Fig. 4 is a longitudinal section thereof with the bolt and spring in elevation.

In carrying out my invention as herein embodied, 5 represents a chair which will serve 50 to illustrate an application of my invention

including a body frame 6 and an adjustable back frame 7. The body frame may be of any desirable formation and preferably such that it can be upholstered. Said body frame includes two uprights 8 which serve to support the back frame and preferably form the rear legs as well as the back of said body frame.

The back frame 7 may also be constructed so as to be upholstered and includes a pair of side members 9 which are naturally properly braced or joined to cross pieces. This back frame is swingingly mounted at or near its lower end on a rod or axle 10 which passes through the sides 9 and has its ends mounted in the uprights 8 of the body frame, and if found desirable, a bearing hole 11 may be provided in a keeper plate 12 for said ends of the rod or axle, which keeper plate is mounted on the inside face of each upright 8 and may be provided with keeper holes 13 for the bolts to be presently described. Of course it will be understood that the keeper plates may be eliminated and the holes 13 and 11 formed directly in the uprights 8.

An operating rod 14 is slidably mounted in the sides 9 of the back frame at a suitable position above the upper ends of the uprights 8 so that said uprights will not interfere with the proper operation or adjustment of the back frame. In other words, the operating rod 14 must be high enough so as not to contact with any part of the body frame, especially the uprights 8 during adjustment of the back frame and said operating rod projects across the space between the two sides 9 of the back frame and one or both ends of said operating rod extends outside of the back frame so as to be readily gripped and manipulated by a person desiring to adjust the back frame, and the outside extending end or ends may each be provided with a knob 15.

While it will be obvious from the later description that said operating rod does not have to be spring actuated in one direction, yet I prefer that it be so and I therefore provide a casing 16 similar to that shown in Figs. 3 and 4, which may be mounted in either or both of the sides 9 of the back frame with the casings 16 embedded in the side members 9 and the ears or flanges 30 secured to the outer 100

faces of said side members with the operating rod, passing therethrough, and a spring housed in the casing and engaging a shoulder formed on the operating rod, as the movable 5 element, and another shoulder in the casing, as the stationary element, so as to generally force said operating rod toward the right hand side of Figure 1.

To the operating rod 14 adjacent one of the 10 sides 9 of the back frame is pivotally connected one end of a long lever 17 as at 18, the said lever being pivoted intermediate its ends to a bracket 19 secured to the inside surface of one of the sides 9, while the opposite end of 15 said long lever is pivotally connected with a spring actuated bolt 20. The bolt 20 is mounted in a casing 16 similar to the ones described in connection with the operating rod with a spring 21 coiled thereabout and 20 having one end engaging a shoulder 22 in the casing, and the other end a shoulder 23 on the bolt which will thus normally force said bolt toward the contiguous upright 8 and cause 25 said bolt to register with one of the keeper holes 13 whenever properly aligned therewith.

To the operating rod 14 adjacent the other side 9 of the back frame is pivoted one end of a short lever 24 as at 25 which lever is pivoted 30 intermediate its ends to a bracket 26 secured to the inside face of said other side 9, and the inner or lower end of said short lever is connected by a link 27 with the upper or outer end of a second short lever 28, the latter being 35 also pivoted intermediate its ends to a bracket 29 mounted on the inside surface of said other side 9 of the back frame. The inner or lower end of the second short lever 28 is pivotally connected to another spring actuated bolt 20 similar in all respects to the first mentioned 40 one since in both instances the bolts must be urged outward by the springs for registration with keeper holes in the inside surface of the uprights 8.

Whenever the invention illustrated herein is used on or with an upholstered article of furniture practically all of the operating parts will be invisible except for one or both projecting ends of the operating rod and the knob or knobs thereon.

When it is desired to adjust the back frame to some position other than shown in Fig. 1, the operating rod is manually actuated toward the left hand side of Fig. 1, which, through the combination of levers, will withdraw the spring actuated bolts from the uppermost keeper holes and therefore said back frame may be swung backward, outward or downward, until the spring actuated bolts are moved into alignment with one of the other keeper holes 13 in each body frame upright, and at such time, the operating rod may be released and the springs acting on said operating rod and bolts will move 60 the latter into the aligned keeper holes 65

whereby the back will be properly supported.

Of course I do not wish to be limited to the exact details of construction as herein shown, as these may be varied within the limits of the appended claims without departing from the spirit of my invention.

Having thus fully described my invention, what I claim as new and useful is:

1. An adjustable article of furniture consisting of a body frame including a pair of uprights, a rod extending across the space between and having its ends mounted in said uprights, an adjustable frame swingingly mounted adjacent its lower end on said rod within the space between said uprights, 75 spring actuated bolts carried by the adjustable frame for registration with any of a number of keeper holes in the uprights, a rod slidably mounted in the adjustable frame adjacent its upper end and above the upper 80 ends of the uprights, and a set of levers connected with said sliding rod and the bolts whereby said bolts may be simultaneously withdrawn from the keeper holes against the action of the springs upon manual manipulation of said sliding rod in the proper direction.

2. In a device of the kind described, a body frame including a pair of uprights in spaced relation, a rod disposed across the space between and having its ends mounted in said uprights, a frame including a pair of sides swingingly mounted adjacent its lower end on said rod, spring actuated bolts passing through said sides for selective registration 95 with keeper holes in the uprights, and mechanism operable manually from a point at the top of the adjustable frame above the upper ends of the uprights for simultaneously actuating the bolts against the actions of the 100 springs to withdraw said bolts from the keeper holes.

3. An adjustable article of furniture consisting of a body frame including a pair of parallel spaced uprights, a rod disposed between and having its ends mounted in said uprights adjacent their lower ends, said uprights having bolt keeper holes formed in the inside surfaces in arcs of circles whose axes correspond to the axis of the rod, a back 110 frame swingingly mounted adjacent its lower end upon said rod within the space between the uprights and of a length sufficient to project above the upper end of said uprights, 115 spring actuated bolts mounted in the sides of the adjustable back frame and passing entirely therethrough whereby their outer ends may be caused to register with selected ones of the keeper holes, an operating rod slidably mounted in the adjustable back frame adjacent its upper end above the upper ends of the uprights and having at least one end extending outside of said back frame, a bracket secured to one of the sides of the back frame, a lever pivoted intermediate its ends in said 120 125 130

bracket and having one end pivotally connected with a bolt, and the other end pivotally connected with the operating rod, a pair of brackets secured to the other side of the

5 back frame, and levers pivoted intermediate of their ends in said brackets with the adjacent ends of both levers connected to a link and the opposite end of one of said levers being pivotally connected to another of the
10 bolts and the opposite end of the other lever pivotally connected to the operating rod whereby the longitudinal movement in one direction of said operating rod will simultaneously withdraw the bolts from their keeper
15 holes to permit of selective adjustment of the back frame.

4. The structure set forth in claim 3, wherein the operating rod is spring actuated in one direction.

20 In testimony whereof, I have hereunto affixed my signature.

STEFAN SCHNEIDER.
